UNITED STATES PATENT OFFICE.

CHARLES LA DOW, OF ALBANY, NEW YORK, ASSIGNOR TO THE SELF-SHARPENING PLOW COMPANY, OF SAME PLACE.

DESIGN FOR A PLOWSHARE-PATTERN.

SPECIFICATION forming part of **Design No. 31,943**, dated December 5, 1899.

Application filed April 26, 1899. Serial No. 714,617. Term of patent 14 years.

To all whom it may concern:

Be it known that I, CHARLES LA DOW, a citizen of the United States, residing at the city of Albany, county of Albany, State of New York, have invented and produced a new and original Design for a Plowshare-Pattern, of which the following is a specification, reference being had to the accompanying drawings, forming a part thereof, in which—

10 Figure 1 is a plan. Fig. 2 is a reverse plan. Fig. 3 is a section along the lines 3 3 of Fig. 1.

Similar letters refer to similar parts throughout the several views.

15 The leading or material feature of my design consists in a plowshare-pattern having its molding-bed A substantially triangular in outline and having projected from the molding-bed A on one side thereof a plowshare-

shaped portion B, said portion B being in cross-section concave on one side and convex on the other, as shown in Fig. 3. As thus arranged the plowshare-pattern has the design on one side of the face of the plowshare and on the other side on the back of the plowshare. 20

Having described my invention, what I claim as new, and desire to secure by Letters Patent, is—

25 The design for a plowshare-pattern, as herein shown and described. 30

Signed by me at Albany, New York, this 24th day of April, 1899.

CHARLES LA DOW.
